POLE CLIMBER WITH AUTOMATIC IMPACT DRIVE

Roland A. Merrill, Van Nuys, Calif.

Application January 20, 1951, Serial No. 206,965

14 Claims. (Cl. 227—27)

1

This invention relates to linesman's pole climbers or climbing irons. The general object of the invention is to provide a climber having means for automatically setting the claw of the climber into a pole to an adequate depth for safely sustaining the weight of the linesman, without requiring any effort on the part of the linesman other than that of simply imposing his weight upon the climber.

When a linesman is ascending a pole, the action of setting the claws of the climbers into the pole is usually vigorous enough to embed them to an adequate depth to prevent them from slipping or tearing loose when the full weight is imposed thereon. However, when a linesman is moving horizontally around the pole he will often fail to set a claw of a climber sufficiently deeply into a pole to prevent slipping and sometimes a bad fall will result from a claw tearing loose from the pole because of insufficient embedment.

My invention contemplates an automatic mechanism for imparting a sharp blow to the pole, from a striker operating under spring pressure which is stored up when the weight of the linesman is applied to the climber. Means is provided for releasing the striker when a predetermined spring loading has been reached, so that the full spring load may be utilized for driving the striker against the claw in striking a blow that will drive the claw deeply into the pole.

A further object of the invention is to provide in a climber having such an automatic striking mechanism, a means for automatically resetting the striker mechanism for a subsequent operation, when the weight of the linesman is released from the climber.

A specific object of the invention is to provide a climber having an automatic claw setting mechanism as outlined above, and which is of relatively simple, durable and inexpensive construction.

Other objects will become apparent in the ensuing detailed description of the invention, taken together with the appended drawings, in which:

Fig. 1 is a side view of a climber embodying my invention;

Fig. 2 is an axial sectional view of the climber, with the parts showing the relative positions assumed at an early stage in the loading operation, and with the unstressed position of the parts indicated by dotted lines;

Fig. 3 is an axial sectional view of the climber showing the parts in the position in which the striker actuating spring is fully loaded and the striker is about to be released for its operating blow;

Fig. 4 is an axial sectional view of the climber showing the parts in the relative positions just prior to the striking of the blow;

2

Fig. 5 is a transverse sectional view taken on the line 5—5 of Fig. 2;

Fig. 6 is a transverse sectional view taken on the line 6—6 of Fig. 2;

Fig. 7 is a transverse sectional view taken on the line 7—7 of Fig. 2; and

Fig. 8 is a detail of one of the trigger pawls.

Referring now to the drawings in detail, I have shown, as an example of one form in which the invention may be embodied, a climber having a foot stirrup 10 adapted to extend beneath the instep of a linesman's shoe and to be secured thereto by a strap (not shown) extending through an eye 11 in the outer extremity thereof, and strapped around the foot in a conventional manner whereby the climber is attached to the foot and the linesman's weight may be carried upon the stirrup 10.

The climber has a claw 12, provided with a sharp point for entering a telephone or electric power line pole, claw 12 being connected to the stirrup 10 through the medium of the automatic driving mechanism which will now be described.

Secured to an arm 13 forming an upward extension of the inner end of stirrup 10 is a casing 14 the upper portion of which defines a cylindrical chamber 15 in which an annular striker 16 is longitudinally slideable. Striker 16, as shown in the dotted line position of Fig. 3, normally rests against a shoulder 17 defining the lower extremity of chamber 15 and the upper extremity of a thickened lower wall portion of casing 14, in which is formed a pair of diametrically opposed longitudinal slots 18. A heavy coil spring 19, for actuating the striker, is interposed under compression between striker 16 and a collar 20 which is threaded into the upper end of chamber 15. The lower end of spring 19 is piloted in a counterbore in the upper end of striker 16. Collar 20 may have sockets 21 for engagement by a spanner wrench. The initial loading of spring 19 may be adjusted by adjusting collar 20 to different depths in casing 14. A bearing bushing 22 is threaded through collar 20.

Claw 12 is provided with an integral annular collar 47, to receive the impact of striker 16. A cross-pin 23 extends therethrough and is secured therein. The ends of cross-pin 23 are keyed in slots 18, to restrain claw 12 against rotation in casing 14 while allowing it to slide longitudinally therein. Claw 12 has a stem 24 which extends upwardly through a central bore in bushing 22 and is fitted therein for free sliding movement. Claw 12 has a cylindrical main shaft portion 25 which is fitted into the bore of annular striker 16 for free sliding movement therein.

Stem 24 joins shaft portion 25 to define a squared annular shoulder 26. In the loading of spring 19 (Fig. 2) when the weight of the oper-

ator is imposed upon stirrup 10, shoulder 26 is engaged by a pair of pawls 27 each pivoted, on a pivot 28, in a recess 29 opening into the bore of striker 16. The recesses 29 are preferably spaced equidistantly around the circumference of striker 16. There may, for example, be three of the pawls 27 disposed at 120° intervals, (Fig. 6) in order that the loading may be well distributed. Each of the pawls 27 has at its lower end a shoulder 38 (Fig. 8) for engaging shoulder 26 of claw 12, and a finger 39 at the outer extremity of the shoulder 38, to engage the side of claw shaft 25 and thus limit the inward movement of the pawl. Each of the pawls is engaged by a split ring spring 30 disposed in an internal annular groove 31 in striker 16 and engaged in notches 32 in the pawls. The slots 29 are of sufficient depth so that the pawls 27 may retract outwardly to positions, as shown in Fig. 3, where they clear the shoulder 26 and allow the striker 16 to be driven by the loading spring 19 downwardly against collar 47, whereby to deliver a blow to the claw 12.

Projecting downwardly from the lower end of bushing 22 is a thin walled tubular pawl releasing plunger 33 which is adapted to enter the upper end of the bore of striker 16, to engage the pawls 27, and to move them outwardly until they are completely released from the shoulder 26. Bushing 22 has at its upper end a head 34 which is of non-circular shape so that a wrench may be applied thereto. The adjustment of bushing 22 is for the purpose of adjusting pawl release plunger 33 to the proper position for releasing pawls 27 at a point of maximum loading of spring 19. Plunger 33 has a counterbore 35 which, with stem 24, defines an annular space in which is received the upper portion of a light coil spring 36. The spring 36 is engaged under compression between bushing 22 at its upper end and, at its lower end, an annular groove 37 in shoulder 26. The function of spring 36 is to assure the return movement of claw 12 to a starting position in which pin 23 is at the lower ends of slots 18, when the linesman raises his foot so as to elevate casing 14. This starting position must be attained in order that pawls 27 may reengage shoulder 26.

Casing 14 has a reduced lower end portion 40 which has a cylindrical external wall forming a bearing surface for a locking sleeve 41 that is rotatably mounted thereon. Sleeve 41 has diametrically opposed L-shaped slots including vertical slot portions 42 adapted to register with casing slots 18, and including slightly inclined (helical) lateral slot portions 43. Slot portions 43 are adapted to receive the end portions of pin 23 when locking sleeve 41 is rotated, whereby to draw said end portions of the pin tightly against the lower ends of the slots 18 and to thereby lock the claw 12 in its starting position. Thus the climber may be converted into a climber having conventional operational characteristics, the weight of the linesman being transmitted from casing 14 to sleeve 41 (through a shoulder 44 in casing 14 at the upper extremity of reduced end portion 40) and from sleeve 41 to pin 23.

A collar 45 is threaded into the lower end of casing 14, and has a radial flange 46 which functions as a retainer bearing against the lower end of locking sleeve 41.

The operation of the climbers is as follows: One of the climbers is strapped to each foot with claws 12 directed inwardly toward each other so that they may be impaled in the post to be climbed. At the starting point pin 23 is at the bottom of slots 18 as indicated in dotted lines in

Fig. 2, and pawls 27 have thus been permitted to move inwardly under the pull of ring spring 30, and are engaged against shoulder 26 so that springs 19, 36 may be compressed. The point of the claw is pressed against the pole at a selected point, and the weight of the body is applied to the stirrup attached thereto. As the weight is applied, the claw will enter the post to a degree determined by the aggregate loading upon springs 19 and 49, and at the same time the springs will be compressed in accordance with the resistance of the wood to the penetration of the claw. An early stage in this loading operation is shown in Fig. 2, which shows the stirrup and casing 14 moving downwardly, compressing the springs. This movement continues until shoulder 17 passes below pin 23. The loading movement is terminated by the engagement of shoulder 26 against the lower end of plunger 33 (Fig. 3). In the final stage of loading movement, the plunger 33 will engage and spread pawls 27. Thus the striker 16, which up to this point has been supported upon shoulder 26, will be released for downward movement relative to casing 14 and claw shaft 25. After the disengagement of the pawls, striker 16 will be propelled downwardly by the stored energy of compressed spring 19. During this interval, the weight of the operator upon stirrup 10 will be transmitted through casing 14, plunger 33 and shoulder 26 to claw 12, which remains in a fixed position, impaled in the post. The striker 16 as it nears the end of its downward stroke, will strike a sharp blow against pin 23.

Upon contact with pin 23, striker 16 will release the kinetic energy stored therein during its downward travel, driving claw 12 more deeply into the post. Maximum possible travel of claw 12 under the blow, is determined by the distance that pin 23 projects above shoulder 17, the engagement of striker 16 against shoulder 17 terminating the downward travel of the striker in the chamber 15. Fig. 4 shows the extent of projection of pin 23 above shoulder 17 prior to the striking of the blow, as determined by the engagement of shoulder 26 against plunger 33.

After the blow has been absorbed by the claw, the casing 14 will follow the claw downwardly until plunger 33 again makes contact with shoulder 26, thus establishing a solid supporting connection from the claw to the stirrup 10. The load capacity of spring 19 is selected so as to obtain adequate setting of the claw into the post to prevent any possible disengagement when the full weight of the operator is loaded upon the stirrup 10. At the same time, the load capacity of the spring 19 must be sufficiently below the weight of the average operator so that it will be possible for the spring to be fully compressed to the fully loaded position of striker 16, before the full weight of the operator is applied to the stirrup. Otherwise, the striker could not be released.

The preloading of the spring 19 may be varied within limits by adjusting the position of abutment collar 20. By reducing the preloading, the apparatus may be adjusted to a lighter person, and by increasing the preloading the apparatus may be adjusted to a heavier person.

By changing the position of plunger 33, the point of triggering of the pawls 30 to their disengaged positions, may be varied. Such adjustment likewise may be utilized for adjusting the climber to a lighter or heavier person. The earlier the point of disengagement, with reference to the loading of spring 19, the less the compression of spring 19.

When the weight of the operator is released from the stirrup, and the casing 14 is moved upwardly, relative downward movement of claw 12 in relation to casing 14 will be assured by the operation of spring 36, i. e., claw 12 will be held by spring 36 against moving upwardly with casing 14 until the latter has returned to the position of Fig. 1 in which pawls 27 have reengaged above shoulder 26. This completes the cycle of operation of the apparatus.

I claim:

1. In a linesman's climber, a stirrup, an elongated casing secured to said stirrup, a claw having a shaft extending into said casing, and having an abutment member, a striker slideable longitudinally within said casing and adapted to engage said abutment member, a spring under compression between the upper end of said striker and the upper end of said casing, for driving said striker downwardly relative to said shaft, a trigger element carried by said striker and releasably engageable with said shaft to load said spring by relative upward movement of said striker in said casing when the casing is moved downwardly under the weight of the operator, and means carried by the upper end of said casing and rendered operative by the arrival of the casing at a downward limit of movement relative to said shaft, to release said trigger from its engagement with said shaft and thereby cause the striker to be propelled downwardly by the loaded spring and to strike a blow against said abutment member, whereby to drive said claw into a body engaged thereby.

2. In a linesman's climber, an elongated casing having means to secure the same to a linesman's shoe, a claw having a shaft extending into said casing and having an abutment member, an annular striker encircling said shaft and slideable longitudinally within said casing and relative to said shaft, for engagement with said abutment member, a spring under compression between the upper end of said striker and the upper end of said casing, for driving said striker downwardly, a plurality of trigger elements carried by said striker in annular array and releasably engageable with said shaft to support said striker on the shaft while the casing is moved downwardly under the weight of the operator, whereby to load said spring, and means carried by the upper end of said casing and rendered operative by the arrival of the casing at a downward limit of movement relative to said shaft, to release said trigger from engagement with said shaft and thereby cause the striker to be propelled downwardly by the loaded spring, and to strike a blow against said abutment member, whereby to drive said claw into a body engaged thereby.

3. In a linesman's climber, an elongated casing adapted to be secured to a climber's shoe, a claw having a shaft extending into said casing and having an abutment member, a striker slideable longitudinally within said casing and along said shaft and adapted to engage said abutment member, a spring under compression between the upper end of said striker and the upper end of said casing, for driving said striker downwardly relative to said shaft, trigger means for establishing a releasable connection between said striker and said shaft to load said spring by supporting said striker on said shaft while the casing is moved downwardly under the weight of the operator, whereby to load said spring and releasing means carried by the upper end of said casing and rendered operative by the arrival of the

casing at a downward limit of movement relative to said shaft, to engage said trigger means and release said striker supporting connection, thereby to cause the striker to be propelled downwardly by the loaded spring and to strike a blow against said abutment member so as to drive said claw into a body engaged thereby.

4. A climber as defined in claim 3, wherein said releasing means comprises a tubular member secured to the upper end of the casing and projecting downwardly therein, said shaft having a reduced stem extending upwardly through said tubular member and having a shoulder defined at the base of said stem, against which said tubular member is engageable to provide said solid support.

5. A climber as defined in claim 4, wherein said tubular member is spaced from said stem to define an annular space, said climber including a relatively light coil spring the upper end of which is engaged in said annular space and the lower end of which is engaged against said shoulder, for effecting return movement of said shaft downwardly with reference to the casing when the casing is lifted.

6. In a linesman's climber, an elongated casing having means for securing the same to a linesman's shoe, a claw having a shaft extending into said casing and having an abutment member slideably engaged with said casing for preventing rotation of the claw with reference to the casing while allowing longitudinal movement of the shaft in the casing, an annular striker encircling said shaft and slideable longitudinally within said casing for engagement with said abutment member, a coil spring under compression between the upper end of said striker and the upper end of said casing, for driving said striker downwardly relative to said shaft, trigger means for establishing a releasable connection between said striker and said shaft to load said spring by supporting said striker on said shaft while the casing is moved downwardly under the weight of the operator, and means carried by the upper end of said casing and rendered operative by the arrival of the casing at a downward limit of movement relative to said shaft, to engage said trigger means and to release said striker supporting connection, and thereby cause the striker to be propelled downwardly by the loaded spring and to strike a blow against said abutment member, whereby to drive said claw into a body engaged thereby.

7. In a linesman's climber, an elongated casing having means for securing the same to a linesman's shoe, a claw having a shaft extending into said casing and having an abutment pin extending transversely therethrough, said casing having a pair of opposed longitudinally extending slots in which the ends of said pin are engaged for preventing rotation of said claw relative to said casing while allowing longitudinal movement of the claw relative to the casing, an annular striker encircling said shaft and slideable longitudinally within said casing for engagement against said abutment member, a coil spring also encircling said shaft within said casing and under compression between the upper end of said striker and the upper end of said casing, for driving said striker downwardly relative to said shaft, trigger means for establishing a loading connection between said striker and said shaft for supporting said striker on said shaft while said casing is moved downwardly under a linesman's weight, whereby said coil spring will be loaded, and means carried

by the upper end of said casing and rendered operative by the arrival of the casing at a downward limit of movement relative to said shaft, to engage said trigger means so as to release said loading connection and thereby cause the striker to be propelled downwardly by the loaded spring and to strike a blow against said abutment member, whereby to drive said claw into a body engaged thereby.

8. A climber as defined in claim 7, including a locking sleeve rotatably mounted on the lower end of said casing and having therein L-shaped slots including longitudinal portions adapted to register with the slots of said casing and to receive the ends of said pins, and including transverse portions into which the ends of said pins may be locked when said sleeve is rotated, for locking the claw in a fixed position relative to the casing.

9. A climber as defined in claim 8, wherein said casing has a lower portion of reduced diameter providing an external bearing surface for said locking sleeve, has a shoulder defined at the upper extremity of said reduced portion, engaged by the upper end of said locking sleeve for transmitting load from said casing to said claw; said casing being provided with a collar threaded into its lower end and having a flange extending radially and providing a bearing abutment for the lower end of said locking sleeve, said claw extending through said collar.

10. A climber as defined in claim 7, wherein said casing has in its lower portion an internal shoulder against which said striker may engage so as to limit the downward movement thereof, said abutment pin being projected above said shoulder in the fully loaded position of the climber.

11. In a linesman's climber, an elongated casing, means for attaching the same to a linesman's shoe, a claw having a shaft extending into said casing and having an abutment member, an annular striker encircling said shaft and slideable longitudinally within said casing and along said shaft for engagement against said abutment member, a spring under compression between the upper end of said striker and the upper end of said casing, for driving said striker downwardly relative to said shaft, said striker having a plurality of upwardly opening slots in its upper portion, a corresponding number of triggers each received within a respective slot and pivotally connected to said striker at its upper end, for lateral swinging movement of its lower end, said shaft having shoulder means against which the lower ends of said triggers may engage when swung inwardly, in order that said striker may be supported upon said shaft while said casing is moved downwardly under the weight of a linesman, whereby to load said spring, means yieldingly urging said triggers inwardly, and means carried by the upper end of said casing and rendered operative by the arrival of the casing at a downward limit of movement relative to said shaft, to release said triggers from their engagement with said shaft and thereby cause the striker to be propelled downwardly by the loaded spring and to strike a blow against said abutment member, whereby to drive said claw into a body engaged thereby.

12. A climber as defined in claim 11, wherein said means for urging said pawls inwardly comprises a split ring spring, and wherein said pawls have in their outer sides, notches in which said

ring is engaged, said striker having an internal annular groove receiving said ring spring.

13. In a linesman's climber, an elongated casing having means for securing the same to a linesman's shoe, an abutment collar threaded into the upper end of said casing and adjustable longitudinally in the casing when rotated, a bearing bushing threaded through said collar and adjustable longitudinally of the casing when rotated therein, a claw having a shaft extending into said casing and having an abutment member, said shaft having a stem projecting from its upper end into said bushing and slideable therein, said shaft having a shoulder defined at the base of said stem, an annular striker encircling said shaft and slideable longitudinally within said casing for engagement against said abutment member, a coil spring under compression between the upper end of said striker and said abutment collar, for driving said striker downwardly relative to said shaft, trigger means for establishing a loading connection between said striker and said shaft whereby said striker may be supported upon said shaft while said casing is moved downwardly under the weight of a linesman, compressing said coil spring, resilient means yieldingly biasing said trigger means for establishing said loading connection at the downward limit of movement of said casing relative to said shaft, a tubular releasing plunger constituting a downward extension of said bushing, engageable against said shoulder at the said lower limit of movement of the casing relative to the shaft, to provide a positive load transmitting connection between the casing and the shaft, and to establish said downward limit of movement of the casing, said releasing plunger being engageable with said trigger means as it approaches said downward limit and operative by said engagement to release said loading connection whereby said striker may be propelled downwardly by said spring to strike a blow against said abutment means for driving said claw into a body engaged thereby, and a relatively light coil spring received between said stem and said tubular releasing member, engaged under compression between said bearing bushing and said shoulder, for moving said shaft downwardly relative to said casing when the casing is lifted.

14. A climber as defined in claim 13, wherein said trigger means comprises a plurality of trigger members each pivoted at its upper end to said striker, and each having its lower end adapted to engage against said shoulder to establish said loading connection, said resilient means acting upon said trigger elements to urge them inwardly toward engagement with said shoulder, said trigger elements being inclined inwardly at the lower ends when thus engaged against said shoulder, and said tubular releasing member having a wedging engagement against the inclined inner side of said trigger elements to spread them apart for releasing said loading connection.
